UNITED STATES PATENT OFFICE.

BENJAMIN G. BROOKS, OF MANCHESTER, NEW HAMPSHIRE.

IMPROVEMENT IN APPARATUS FOR DISCHARGING EXTRANEous COLORING MATTERS, &c., FROM PRINTED FABRICS.

Specification forming part of Letters Patent No. 119,503, dated October 3, 1871.

To all whom it may concern:

Be it known that I, BENJAMIN G. BROOKS, of Manchester, in the county of Hillsborough and State of New Hampshire, have invented certain Improvements in Discharging Extraneous Coloring from Printed Fabrics, of which the following is a specification:

The nature and object of the invention relates to the manner of discharging superfluous or extraneous color or other impurities from printed fabrics by causing the fabric, after it has passed through the chlorine-bath in the ordinary mode of bleaching, or the equivalent bleaching process, to pass into a box wholly or partially closed, and therein stretching it in one or more thicknesses in a continuous line over a series of rollers, and when thus stretched subjecting it to the direct action or blast of a succession of jets of high-pressure steam on one or other or both sides of the fabric, either alternately or at the same time, from a series of perforated steam-pipes or their equivalents; the steam jets being so arranged and at such distances from the line of stretched fabric that the jets of high-pressure steam shall be driven from the perforations in the steam-pipes or other means of conveying it directly against the surface of and through the fabric; the fabric being moved in a regular and even manner over the rollers and near the steam jets, so that each part of the fabric is acted upon by the steam jets; the fabric being retained in the box or steam-chest with the discharged steam long enough to thoroughly remove, by means of the steam jets and the steam inclosed in the box or steam-chest, all the chlorine or any extraneous coloring from the fabric; and thence the fabric passes into a cold-water bath, and is then further manipulated in any of the well-known modes.

The advantages gained by this mode of operation are, that all extraneous matters or colors left in the fabric in the preceding processes are more fully discharged, and the action of the steam is to raise or brighten the colors intended to be permanent in the fabric, and at the same time gives a clearer and better white in the portions of the fabric intended to be unacted upon in the

printing or dyeing process; the effect of the use of chlorine being to flatten the colors, while by using high-pressure steam one-half of the amount of chlorine usually employed can be saved, and its injurious effects on the colors intended to remain fixed in the fabric is in a great measure prevented.

The operation of this process is shown in the annexed drawing, in which Figure 1 represents a plan of the interior of the box or steam-chest in which the fabric is acted upon by the steam. Fig. 2 is a perpendicular section, through the box or steam-chest, on the line O R.

The same letters refer to corresponding parts in the drawing.

A A is the outside of the closed box or steam-chest. B B is the line of cloth stretched over the rollers C C, and moving in the direction shown by the arrows from the chlorine bath F to the cold-water bath D. P P are perforated steam-pipes, through the perforations a a of which the steam passes, as shown at E E, against and through the stretched fabric, thereby discharging the extraneous coloring or other impurities, heightening the colors intended to remain, and cleaning and brightening the white or uncolored portion of the fabric as each part of the line of the fabric is successively brought over and under the perforations a a and the jets of steam issuing therefrom.

What I claim as my invention, and desire to secure by Letters Patent, is—

The process of discharging extraneous coloring and other impurities from printed or dyed fabric by the action of jets of high-pressure steam driven against and through the fabric, when so stretched that the jets may operate against one or the other or both sides of the fabric from perforated steam-pipes or their equivalents, substantially in the manner and for the purposes herein set forth.

BENJ. G. BROOKS.
